UNITED STATES PATENT OFFICE.

ROBERT ARTHUR WILLIAMS, OF LLANWNDA, NEAR CARNARVON, WALES.

IGNITION DEVICE FOR INTERNAL-COMBUSTION ENGINES.

1,369,594.

Specification of Letters Patent. Patented Feb. 22, 1921.

Application filed September 9, 1920. Serial No. 409,218.

To all whom it may concern:

Be it known that I, ROBERT ARTHUR WILLIAMS, a subject of the King of Great Britain, and a resident of Porth-yr-Aur, 5 Llanwnda, near Carnarvon, North Wales, have invented new and useful Improvements in Ignition Devices for Internal-Combustion Engines, of which the following is the specification.

- 10 The object of this invention is to provide an ignition apparatus or device for igniting purposes in internal combustion engines which is simpler in construction and operation, and cheaper to produce as an article 15 of manufacture than the ordinary magneto, a further advantage and a great one in practice being that there are no rotating coils or contact pieces. The apparatus will therefore be simpler in the matter of adjustment 20 and timing while it will give the same results as the ordinary commercial magneto of the type as usually constructed. Further, the igniting apparatus according to this invention being without a multiplicity of 25 minute working parts found in the ordinary magneto is more robust and more reliable, also the spark is always at its maximum however much the timing is advanced or retarded.
- 30 In carrying out my invention I provide a permanent magnet, straight or curved, the latter being preferably of the horseshoe pattern, and I bolt or secure the magnet to the flywheel or other rotating part of the engine. 35 If a curved magnet, or magnet of the horseshoe pattern is employed then I prefer to form a slot in the disk of the flywheel adjacent to and within the rim, and I pass the magnet through the slot in such a manner 40 that it is not magnetically short circuited by the flywheel, and secure the magnet by screws or the like to the rim of the flywheel. The said magnet may be made of two or more magnets, the inner closely fitting within 45 and embraced by the outer, but preferably two such magnets are provided, the outer one of which may be formed with lateral lugs or extensions to form pole pieces. If one such compound magnet is fitted at one 50 side of the flywheel, a balance weight of the same weight is fitted on the opposite side of the flywheel, or two such magnets may be fitted at opposed positions of the flywheel rim.
- 55 With the above and other objects in view, which will appear as the description pro-

ceeds, my invention consists in the novel details of construction and arrangement of parts described and illustrated in the following specification and drawings, and 60 while I have described and illustrated the preferred embodiments of my invention, it will be understood that such changes may be made as will fall within the scope of the appended claims. In the drawings:— 65

Figure 1 is an elevation of a flywheel having a single compound permanent magnet secured thereto with an end view of the armature.

Fig. 2 is a view at right angles to Fig. 1 70 partly in section.

Fig. 3 is an elevation in which two permanent magnets are secured in an opposed and balanced manner upon the flywheel.

Fig. 4 is an elevation of another mode of 75 carrying my invention into effect in which a straight bar magnet is employed instead of a horseshoe, the magnet preferably being formed as two magnets in one piece.

Fig. 5 is an elevation in which two armatures are employed with one bar magnet.

Fig. 6 is a transverse section of Fig. 5.

Fig. 7 shows another method of making and breaking contact.

Fig. 8 is a diagram of the connections. 85

A represents the flywheel or other suitable rotating part of the internal combustion engine. B is the shaft on which it is secured. C is the permanent magnet mounted on the flywheel secured by screws or the like. The horseshoe magnet is passed through a slot C' in the disk web of the flywheel so that the magnet poles C² C³ are located adjacent the rim and on each side of same as shown in Fig. 2. A balance weight 90 D is secured on the flywheel at the opposite diametral position to balance the weight of the magnet C. The laminated core E is fixed upon some suitable stationary part of the engine and in such a position that the 95 poles of the permanent magnet during its rotation register with or pass very close to, except for the minimum of clearance for rotation, the poles E¹ E² of the core E. The core E is laminated as shown in Figs. 1, 3, 105 4 and 5, and it is provided with the two windings E³ E⁴ as shown in Figs. 2 and 6. The low tension or primary winding E³ is connected to the framework of the engine. The high tension or secondary winding E⁴ 110 is connected at one end to the low tension winding and at the other end to the spark

- plug or distributor, if the latter be employed. The spring contact plate F is mounted on an insulated support that may be adjustable adjacent the electro-magnet 5 E and it has a wire connecting the end of the plate with the junction of the high tension and low tension windings. On the rim face of the flywheel is secured by screws or the like the brass contact piece G which has 10 fitted thereon flush with its surface (which surface is slightly raised above the flywheel face) a number of insulating gaps or strips H. In the drawings three insulating gaps are shown, but any suitable number of such 15 gaps may be provided. The gaps may be formed by fitting small strips or rods of vulcanite, ebonite or other suitable insulating material within the brass so that the surface of the brass is flush with the surface of 20 the insulating gaps in order not to offer any obstacles or impediment to the spring plate contact or brush passing over it, the end edge of which may be turned over slightly to engage the brass contact piece and gaps. 25 The permanent magnet on the flywheel is so arranged and timed with regard to the cycle of operations of the engine that the rotating or permanent magnet registers with or comes immediately beneath the poles of the 30 armature and at the moment that it is desired that the spark shall pass across the gaps of the sparking plug.
- In Fig. 3 the mechanism described with regard to Figs. 1 and 2 is duplicated by 35 placing another permanent magnet and armature on the opposite side of the same flywheel, all of which duplicated parts as shown operate in a similar manner to that before described with regard to Figs. 1 and 40 2, but the spark produced by the second or duplicate apparatus may be employed to ignite the charge in the second cylinder of the same engine, or alternatively both armatures may be in series or parallel.
- In Figs. 4, 5 and 6, the straight bar magnet is fitted diametrically across the front 45 of the flywheel. The bar magnet K is preferably formed as a double magnet integral that is to say with the two like poles at the center of the bar, so that two like poles, 50 north for example, are at each outside end of same. The bar magnet K is secured to the flywheel by means of the brass bolts and distance pieces L, M, respectively, one bolt at 55 each end. The bar magnet K is formed with a central hole K¹ which fits over the end of the crank or like shaft and is provided with the iron distance piece N. The magnet is secured by the nut shown fixed 60 on the end of the shaft. The flywheel is secured to the shaft in the usual manner as by a key. The fixed armature, high and low tension coils and spring contact plates described with reference to Figs. 1, 2 and 65 3, are arranged and operate in like manner

in Figs. 4, 5 and 6, having a straight bar magnet.

The arrangement shown in Fig. 4 is suitable for a single cylinder two-stroke or for a single cylinder four-stroke without a distributor. In the duplicate arrangement with two fixed armatures shown in Figs. 3, 5 and 6, the second coil should be in parallel with the other coil, and this arrangement is suitable for a two-cylinder two-stroke or a 70 four-cylinder four-stroke engine with a high tension distributor fitted on half time shafts. In Figs. 5 and 6 the crank pin of the engine for which this arrangement forms the igniter should be at 180 degrees. 80

It will be observed that in each of the arrangements shown the brass contact piece G fitted on the face of the flywheel having the previously described connections serves to short circuit the low tension coil and the 85 insulating gaps provide rapid or sudden interruptions of this short circuiting.

Referring to Fig. 7, this shows diagrammatically an alternative method of making and breaking. The fly-wheel A has fitted 90 thereon and projecting from the face of same a small boss or stud O which is of hardened metal. It is adapted to engage with the spring plate P during the rotation of the flywheel and the end of this plate 95 may be provided with a corresponding projection or stud to contact with the stud or projection O. The other end of the spring plate P is fixed to some stationary portion of the engine and earthed. An insulating 100 piece P¹ is secured to the under side of the spring plate P and mounted on the insulator P¹ is the brass plate Q having the wire Q¹ which is connected to the joint of the high tension and low tension coils on the stationary 105 adjustable armature previously described. This connection is indicated on the diagram, Fig. 8. A platinum point P² is secured on the under surface of the plate P adapted to make contact with the corresponding platinum point Q² upon the plate Q, the contact being broken each time that the flywheel A rotates and the stud or projection O engages with and lifts the spring plate P. The wire at the end of the high 110 tension coil, Fig. 8, indicated by the arrow head is connected directly to the spark plug 115 or distributor as may be required.

A condenser may be connected in the circuit as indicated in Fig. 8. 120

The contact points of the make and break may be also placed in the magnetic field so as to magnetically "quench" or break the current flowing in the low tension circuit when the contact points of the make and break are separated, and so produce a higher voltage at the high tension end of the coil.

What I do claim as my invention and desire to secure by Letters Patent is:—

1. An ignition device for internal com- 130

- bustion engines comprising in combination with a fly wheel of an engine having an opening therein, a horseshoe or curved magnet fitted through said opening, in such a 5 manner that the poles of the magnet are on opposite sides of the fly wheel rim, an armature secured to a stationary part of the engine and provided with high and low tension windings, the poles of the magnet, 10 when the fly wheel is rotated, passing in proximity to the poles of the armature, and a make and break mechanism arranged on the rim of the fly wheel.
2. An ignition device for internal combustion engines comprising in combination with a fly wheel of an engine having an opening therein, a horseshoe or curved magnet fitted through said opening, in such a 15 manner that the poles of the magnet are on opposite sides of the fly-wheel rim, and one limb of the magnet is in contact with the fly 20
- wheel and the other limb is spaced therefrom, an armature secured to a stationary part of the engine and provided with high and low tension windings, the poles of the magnet, when the fly wheel is rotated, passing in proximity to the poles of the armature, and a make and break mechanism arranged on the rim of the fly wheel. 25
3. An ignition device for internal combustion engines, comprising in combination with the fly wheel of the engine, having contact points thereon, a stationary armature having high and low tension windings, and spring contact plates connected to said 30 windings, the spring contact plates adapted to be engaged by the contact points on the fly wheel during the rotation thereof. 35

ROBERT ARTHUR WILLIAMS.

Witness:

F. M. WILSON.
